US0D1006611S

(12) **United States Design Patent** (10) Patent No.: **US D1,006,611 S**
(45) Date of Patent: ** Dec. 5, 2023

(54) **BRACKET APPLIED TO A WINDOW TREATMENT**

(71) Applicant: **Lutron Technology Company LLC**,
Coopersburg, PA (US)

(72) Inventors: **Vladislav Pejic**, Allentown, PA (US);
David A. Kirby, Zionsville, PA (US)

(73) Assignee: **Lutron Technology Company LLC**,
Coopersburg, PA (US)

(**) Term: **15 Years**

(21) Appl. No.: **29/828,652**

(22) Filed: **Feb. 28, 2022**

(51) LOC (14) Cl. **08-05**

(52) U.S. Cl.

USPC **D8/363; D6/580**

(58) **Field of Classification Search**

USPC D6/580; D8/363, 373, 376-377, 380

CPC E06B 9/42; E06B 9/72

CLAIM

The ornamental design for a bracket applied to a window treatment, as shown and described.

DESCRIPTION

FIG. 1 is a perspective view of a bracket applied to a window treatment showing our design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment thereof;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines depict structure or features which form no part of the claimed design.

1 Claim, 10 Drawing Sheets
